UNITED STATES PATENT OFFICE.

GENNARO GIUGLIANO, OF WEST HOBOKEN, NEW JERSEY.

PIN-HOLDER.

1,084,327.

Specification of Letters Patent.

Patented Jan. 13, 1914.

Application filed February 5, 1913. Serial No. 746,362.

To all whom it may concern:

Be it known that I, GENNARO GIUGLIANO, a citizen of the United States, and resident of West Hoboken, in the county of Hudson and State of New Jersey, have invented certain new and useful Improvements in Pin-Holders, of which the following is a specification.

The object of my invention is to provide a simple and efficient holder for retaining a row of pins in position to be readily picked from a paper of pins, and whereby a new row of pins may be placed in position as each row is exhausted, the device being cheap to manufacture and convenient in use and operation.

In carrying out my invention I provide a frame or casing adapted to receive a paper of pins and having an open portion near its top adjacent to an upper ledge or bar, upon which a portion of the paper of pins may be laid, and a holding or retaining member adapted to be removably held upon the paper strip at the back of or beyond the row of exposed pins to retain the paper on said ledge or bar.

My invention further comprises novel details of improvement and combinations of parts that will be more fully hereinafter set forth and then pointed out in the claims.

Reference is to be had to the accompanying drawings forming part hereof, wherein,

Figure 1 is a perspective view of a pin holder embodying my invention; Fig. 2 is a section on the line 2, 2, in Fig. 1; and Fig. 3 is a rear view of the pin holder.

Similar numerals of reference indicate corresponding parts in the several views.

In the drawings the numeral 1 indicates a frame or casing, which may be made of any suitable material, such as sheet metal, and is shown in substantially triangular form having a bottom 1^a, a rear wall 1^b and a front wall 1^c, of such dimensions as to receive a paper or package of pins 2 within the frame or casing. The upper edge of the front wall 1^c is spaced from the upper portion of the rear wall 1^b to provide the opening 3, whereby the row of pins 2^a may be exposed above the ledge or bar 1^d, that is located at the upper edge of rear wall 1^b. At least one end 3^a of opening 3 is preferably open to permit ready insertion edgewise of the upwardly disposed portion 2^b of the paper or package of pins, so that the extended part 2^c of the latter may be laid over the ledge or bar 1^d. The front wall 1^c is shown secured to the rear wall 1^b by the extended lug or bent portion 1^e of the front wall soldered or otherwise secured to the rear wall 1^b, whereby the front and rear walls are reliably connected together. Upon the ledge or bar 1^d is attached a retainer 4, adapted to bear upon the rear portion 2^c of the paper of pins, to retain the latter in position with the adjacent row 65 of pins 2^a extending vertically along the rear wall 1^b, with the heads of the pins projecting upwardly in convenient position to be grasped. The retainer 4 may be in the form of a strip of suitable metal, preferably 70 spring-like, such as a strip of spring steel or brass, which is movably or pivotally connected with ledge or bar 1^d by the pivot, eyelet or the like 5, whereby retainer 4 may be swung sidewise when applying or removing 75 the package of pins. The retainer 4 is shown retained in operating position upon the extended portion 2^c of the package of pins by a keeper 4^a engaging the end of the ledge or bar 1^d, such keeper being shown formed by 80 bending or coiling the end of retainer 4 to snap on the end of ledge or bar 1^d. The rear edge 4^b of the retainer 4 is shown bent downwardly to bear down on the extended portion 2^c of the paper, to cause the same to depend or hang down, as illustrated in Fig. 2. At 6 is a pin cushion of any suitable construction, shown having a base member 6^a, a cover 6^b, and a filling of suitable material 6^c, the cushion being shown secured upon the 85 front wall 1^c by the fastening device. At 6 is a pin cushion of any suitable construction, shown having a base member 6^a, a cover 6^b, and a filling of suitable material 6^c, the cushion being shown secured upon the front wall 1^c by the fastening device. In using my improvements the paper or package of pins is opened out slightly to provide the extended portion 2^b, 2^c, and then the same may be slipped edgewise into the 90 pin holder, through the open end of the frame or casing, and through the opening 3, the retainer 4 having first been released from ledge or bar 1^d. The portion 2^c of the paper of pins is laid over ledge or bar 1^d in 95 such position that the upper row of pins will project in position to be grasped, as shown, and retainer 4 is fastened down over the extended part 2^c of the paper of pins, and snapped on the end of ledge 1^d. When the 100 upper or exposed row of pins has been exhausted, part 2^c of the paper may be pulled between the ledge 1^d and retainer 4, until the next row of pins is extended upwardly in position to be grasped, or the retainer may 105 be released and removed when such row of pins is being adjusted to position.

At 8 is a tape, belt or the like shown passing through openings 9 in one of the walls of the holder, and having its ends extended from the frame, whereby said tape may be adjusted upon the pin holder to the proper position, and whereby the pin holder may be fastened around the waist of the user by tying the ends of the tape together or by any suitable fastening thereon. By this means the pin holder may be held upon the person in convenient position to pick off the pins when fitting garments, etc.

Having now described my invention what I claim is:—

- 15 1. A pin holder comprising a frame having walls adapted to receive a paper of pins, adjacent portions of the upper parts of two of said walls being located near together with a space therebetween providing an opening for the passage of a portion of the paper of pins, one of said walls having a ledge bent transversely from said wall to receive a portion of the paper of pins, and a retainer upon said ledge located at one side of the wall to retain an extended portion of the paper thereon with a row of pins exposed in position to be grasped.
- 20 2. A pin holder comprising a frame having walls adapted to receive a paper of pins, adjacent portions of the upper parts of two of said walls being located near together with a space therebetween providing an opening for the passage of a portion of the paper of pins, one end of said opening being
- 25 35 open to admit said portion of the paper edge-wise into said opening, and a flexible retainer pivoted to swing sidewise upon the upper part of one of said walls to retain part of said paper at an edge of one of said walls.
- 30 40 3. A pin holder comprising a frame having walls adapted to receive a paper of pins, adjacent portions of the upper parts of two

of said walls being located near together with a space therebetween providing an opening for the passage of a portion of the paper of pins, one of said walls at its upper corner having a lug secured to the other wall and the opposite ends of said walls being disconnected providing a passage for a portion of the paper of pins, one of said walls having a laterally disposed ledge adjacent said opening to receive a projecting portion of the paper of pins, and a transversely disposed retainer movably attached at one end to said ledge, adapted to overlie a portion of the paper of pins on said ledge, and means to secure the opposite end of said retainer upon the underlying edge of said ledge.

4. A pin holder comprising a frame having walls adapted to receive a paper of pins, adjacent portions of the upper parts of two of said walls being located near together with a space therebetween providing an opening for the passage of a portion of the paper of pins, one of said walls having a lug at its upper corner secured to the other wall and the opposite ends of said walls being disconnected providing a passage for a portion of the paper of pins, one of said walls having a laterally disposed ledge adjacent said opening to receive a portion of the paper of pins, and a flexible retainer movably attached at one end to said ledge near one end thereof, adapted to overlie a portion of the paper of pins on said ledge, said retainer having a bent portion at its free end to snap on the edge of said ledge.

Signed at New York city, in the county of New York, and State of New York, this 3rd day of February, A. D. 1913.

GENNARO GIUGLIANO.
